UNITED STATES PATENT OFFICE.

GRANT E. RUSSELL, OF ST. LOUIS, MISSOURI.

FENCEPOST AND WIRE FASTENER.

1,426,778.

Specification of Letters Patent. Patented Aug. 22, 1922.

Application filed May 7, 1920. Serial No. 379,581.

To all whom it may concern:

Be it known that I, GRANT E. RUSSELL, a citizen of the United States, residing at St. Louis, in the State of Missouri, have invented new and useful Improvements in Fenceposts and Wire Fasteners, of which the following is a specification.

This invention relates to fence posts, and means for securing the line wires of a fence to such a post. It is an object of this invention to provide a fence post of the molded type which is constructed so as to have a plurality of pockets or openings therein to receive fasteners adapted to clamp the line wires of a fence to the post.

The invention also contemplates the provision of a fastener of simple and durable construction which will securely clamp the wires to the post, and may at the same time be readily applied.

It is also an object of this invention to provide a fastener which is constructed of any suitable wire which will lend itself to ready bending so that the same may be bent to shape and applied to the fence post, and without the use of special tools.

The invention consists in the construction of the post and fastener and also in the combination of parts hereinafter described and claimed.

In the accompanying drawings, in which similar characters indicate corresponding parts in all the views,

Fig. 1 is a front elevation of a post showing the wires clamped thereto.

Fig. 2 is a fragmentary vertical sectional view.

Fig. 3 is a view similar to Fig. 2 showing a reinforcing sleeve applied to the fastener.

Fig. 4 is a plan view of the fastener shown in Fig. 3.

Fig. 5 is a side elevational view of a modified form of fastener.

Fig. 6 is a view showing the fastener indicated in Fig. 5 in the condition in which it is adapted to be applied to the wire, and before it is twisted to the shape in which it is inserted in the post pocket, and

Fig. 7 is a view of still another form of fastener.

Referring to the accompanying drawings more in detail, 10 indicates a post which may be of the molded type fashioned from concrete or cement, and provided with a

plurality of spaced transverse openings or 55 pockets 11 therein.

Although, I have shown and described this post as of the molded type, it should also be understood that the same may be constructed of wood, metal or any other suitable material to which my improved fastener means hereinafter described may be applied.

The pockets or openings 11 are shown as extending transversely of the post and entirely through the same, although, of course, it is understood that the same need not be extended entirely through the post. One of the walls of the opening, in this instance the upper wall 12, is inclined toward its opposite wall in the direction of the entrance 70 of the opening which is in the front face 10' of the post. This inclination of the upper wall is for the purpose of cooperating with the fastener means later described so as to retain the fastener or clamp in the opening. 75 For this same purpose the upper wall 12 is also provided adjacent the entrance to the pocket with a shoulder 13 which is engaged by a portion of the clamp, and thus prevents the clamp from being removed 80 therefrom.

The clamp or fastener is formed from a single piece of wire or other suitable material which is at approximately its central portion, bent upon itself, as at 14, to form 85 shanks 15, 16, having ends 15', 16' bent in the same general direction at an angle to and over the shanks toward the central bend 14.

The fastener is adapted to be inserted in 90 the pocket or opening through the entrance thereof in the front face 10' of the post. Upon the insertion of the fastener, the same being formed from wire having a slight degree of resiliency, the end 95 portions of the same are compressed and remain in this compressed position until the fastener is inserted in the pocket a sufficient distance to permit the bent end portions to pass the shoulder 13 whereupon the ends 100 spring forwardly to the position shown in Fig. 2, preventing the removal of the fastener. It is, of course, understood that before the fasteners are inserted in the opening they are passed over the line wires F of 105 the fence.

If it is desired to strengthen the clamp, a stiffening sleeve 17 may be placed over its

end portions so that should an excessive pull be exerted upon the fastener, it will be necessary to collapse and bend not only the angularly disposed end portions, but also the stiffening sleeve 17. In constructing these fasteners it is desirable to bend the end portions in relation to the shanks so that an outward pull on the fastener will be transmitted to the end portions, the ends of which 10 should abut the shoulder in such a manner that the strain will be in the direction of the length of the end portions and not at the bend which they make with the shanks of the fastener. If the fasteners are constructed in this manner, and applied to the 15 post as described, any outward pull upon the fastener will not tend to cause the angularly bent end portions to straighten out with relation to the shanks, but will rather 20 tend to transversely bend the same. Obviously, the application of the stiffening sleeve 17 will materially increase the strength of the fastener.

Referring to Figs. 5 and 6, there is shown 25 a modified form of fastener which is constructed of a single length of spring wire or other suitable material looped at its central portion to form an eye 19 and then bent to the shape shown in Fig. 5 to form shanks 30 20, 21, having end portions 20', 21', extending in the same general direction at an angle to and over the shanks. In applying this fastener to the fence post the same may be positioned on the fence wire in the shape 35 shown in Fig. 6, and after the wire is placed within the eye 19, the shank 21 is bent to the position shown in Fig. 5, whereupon the fastener is inserted in its pocket within the fence post in the same manner as the fastener shown in the remaining views, and as 40 previously described.

In Fig. 7 is shown another type of fastener similar to the fastener shown in Fig. 3 and bent upon itself as at 141 to form shanks 45 15^a, 16^b. The end portions of these shanks are bent to form resilient loops 16^c and then extend at an angle to and over the shanks toward the bend 141 in the same manner as the ends of the fastener shown in Fig. 3. 50 By the formation of the loops 16^c the resiliency of the end portions is increased and thus when the end portions are bent toward the shanks upon inserting the fastener into the openings in the post they have a greater 55 tendency to move from the position into which they are compressed and to lodge behind the shoulder 13.

By reference to Figs. 2 and 3 it will be observed that the fasteners are formed so 60 that the length of the end portions bent at an angle to the shanks is greater than the height of the opening from the floor of the same to the top, this construction being desirable for the reason that an outward pull 65 upon the fastener after the same is inserted

cannot straighten out the fastener without bending the end portions, and when the stiffening sleeves are placed upon these end portions it is thus necessary to bend not only the end portions, but also the sleeves, before the 70 outward pulling stress can remove a fastener.

It should be understood that such modifications may be made in the construction of the post, the formation of the fastener picks, and in the shape of the fasteners as come 75 within the scope of the claims appended hereto. For instance, it may be desirable at times to vary the shape of the upper wall of the pocket so that the shoulder 13 will be 80 more inclined and will not make such a sharp angle with the other portions of the upper wall.

It should further be understood that although I have described my invention as applied particularly to a fence post and to the retention of fence wires upon such a post, obviously, the same is not limited in its application to this particular use and is adapted for use in connection with posts and other objects of a similar character to which wires or the like are to be fastened.

I claim:

1. A fastener for securing the line wires of a fence to a post comprising a shank having an eye at one end by means of which the fastener may be secured to the fence wire, and a portion at the other end bent away from the shank and inclined over the shank, said end portion being of less length than the shank and terminating intermediate the ends of the shanks, the end portion and the shank being adapted to fit within an opening in a fence post whereby the end portion may secure the fastener to the fence post.

2. A fastener formed of a length of wire having a shank, an eye at one end of the shank, a portion at the other end of the shank bent away from and inclined over the shank, and a stiffening means upon said last mentioned portion.

3. A fastener formed of a length of wire having a shank, an eye at one end of the shank, a portion at the other end of the shank bent away from and inclined over the shank, and a stiffening sleeve upon said last mentioned portion.

4. A fastener formed of a length of wire having a shank, an eye at one end of the shank, a portion at the other end of the shank bent away from and inclined over the shank, and a removable stiffening sleeve upon said last mentioned portion.

5. A fastener for securing the wires of a fence to a post comprising a single length of wire having its end portions bent laterally in opposite directions and rearwardly over the main body of the wire, the length of wire being also bent upon itself at its center to dispose the end portions side by side.

side extending in the same direction, said end portions being adapted to fit within openings in a fence post, and the centrally bent portion of the length of wire forming 5 an eye to receive the wires of a fence.

6. A fastener formed from a single length of wire looped at substantially its center to form an eye and having a pair of shanks extending in the same general direction 10 from said loop, said shanks having end portions bent away therefrom in the same direction and inclined over the shanks.

7. A fastener formed from a single length of wire bent upon itself to form shanks, 15 said shanks having ends bent therefrom substantially in the same direction and inclined over said shanks, and stiffening means upon said shank ends.

8. A fastener formed from a single length 20 of wire bent upon itself to form shanks, said shanks having ends bent therefrom substantially in the same direction and inclined over said shanks, and a stiffening sleeve surrounding the ends of said shanks.

9. A fastener formed from a single length 25 of wire looped at substantially its center to form an eye and having a pair of shanks extending in the same general direction from said loop, said shanks having end portions bent away therefrom in the same direction and inclined over the shanks, and a stiffening sleeve surrounding the end portions of said shanks. 30

10. A fastener for securing the wires of 35 a fence to a post comprising a single length of wire looped at its central portion to form an eye, having its end portions bent laterally in opposite directions and rearwardly over the main body of the wire, the length of wire being also bent upon itself at its center 40 to dispose the end portions side by side extending in the same direction, said end portions being adapted to fit within openings in a fence post, and said eye being adapted to receive the wires of the fence. 45

In testimony whereof I have hereunto set my hand.

GRANT E. RUSSELL.
